COWTAIL GARTER

Michael Jamba, Stamford, N. Y.

Application March 12, 1936, Serial No. 68,550

1 Claim. (Cl. 119—105)

This invention may be termed a cow tail garter, the object of the invention being the provision of means for holding a cow's tail against swishing and which can be used not only at milking time but at all times, and especially during the winter months when the cow is stabled so as to prevent the cow from swinging her tail and throwing moisture and dirt about.

A further object of the invention is to provide a device of this character which can be worn by the cow without inconvenience and when in either a reclined or standing position.

The invention together with its objects and advantages will be best understood from a study of the following description taken in connection with the accompanying drawing wherein:

Figure 1 is a view illustrating the application of the invention.

Figure 2 is a plan view of the invention.

Figure 3 is a perspective view of one end portion of the device, and

Figure 4 is a detail sectional view taken on a plane midway between and paralleling the upper and lower edges of the strap and showing the manner of closing the loop at one end of the device.

In accordance with the present invention the "garter" is preferably constructed from a single length of elastic material, and this strip, indicated by the reference numeral 5 may be of any suitable length and width.

On each end of the strip 5 there is provided a hook 6.

The hook 6 may be of any suitable structure and may be applied in any suitable manner to an end of the strip 5. However in the present instance each hook is illustrated as being formed from a single blank of metal or the like bent into a substantial U with one side of the U formed with integral wings 7 adapted to be bent inwardly toward one another to provide with the adjacent side of the hook a sleeve in which one end of the strip 5 is clinched. In this connection as clearly shown in Figure 4 it is preferable to have an end of the strip 5 extend beyond the inner end of the sleeve 7 and within the bight of the U to provide an anti-slipping surface and as indicated at 8.

For each of the hooks 6 there is also provided on the strip 5 a keeper loop 9 which is easily shiftable longitudinally of the strip.

Further the strip 5 is provided adjacent each end thereof with an adjustment frame or slide 10 in a manner as clearly shown in Figure 3 which slide 10 will serve to hold the loop 9 at the desired adjustment and will be used in an obvious manner for increasing or decreasing the size of the loops 11 and 12.

From the above therefore it will be seen that with this device a relatively large loop 11 may be provided for securing the device on the leg of the cow 13 at the desired location and as suggested in Figure 1 while a smaller loop 12 is 15 provided to engage the tail 14 of the cow preferably below the tail bone so as not to in anywise interfere with proper circulation.

As is thought apparent, in applying the device one end portion of the strip 5 forming the loop 7 is passed around the leg of the cow and the hook 6 associated with that end of the strip engaged with its keeper loop 9. The other end of the strip is then passed about the bushy end of the tail 14 preferably below the tail bone and the hook 6 25 associated with this last named end of the strip is engaged with its keeper loop 9 thus forming the loop 12 which embraces the cow's tail. When thus applied the cow will be prevented from swishing her tail to any material extent.

Due to the elastic nature of the strip 5 it will be seen that the device will in nowise interfere with the expansion and contraction of the muscles of the leg and thus the device may be worn at all times without inconvenience to the cow.

Having thus described the invention, what is claimed as new is:

As a new article of manufacture, an elastic strip, hooks on the respective opposite ends of said strip, a pair of slide frames on the strip 40 through which opposite end portions of the strip are doubled back to form loops, and keeper loops confined on the strip through the medium of said slides, and said hooks being engageable with said keeper loops as and for the purpose specified. 45
